MICHAEL MELAMID, OF FREIBURG, GERMANY.

SPLITTING UP OF TARS, CRUDE MINERAL OILS, AND THE LIKE.

Application filed July 5, 1923, Serial No. 649,689, and in Germany April 23, 1923.

This invention refers broadly to a process for the splitting up of mineral oils, tar oils, and the like and of the substances from which they are usually obtained, such as 5 crude tars, crude kerosene and raw naphtha and the like, and it is intended to generally improve the methods of producing light hydrocarbons from such substances in the presence of metals. In a previous application, 10 Serial No. 510,082, filed Oct. 24, 1921, I have described a process for the manufacture of hydrocarbons of comparatively low boiling points from tar oils, mineral oils and the like. In further pursuance of the principles outlined I have ascertained that not 15 only distillation products and fractions from tars, petroleum-products and the like are subject to this kind of decomposition, but that raw materials of this kind, even 20 where they occur as waste products may still be employed with advantage for obtaining such decomposition products. In connection with this procedure it has been found that unforeseen favorable economical 25 and industrial results are accomplished by the fact that in the working of this process the raw materials may be completely converted and without leaving a residue, such as pitch, cokes, asphaltum and the like, very 30 valuable hydrocarbon fluids of low boiling points and lubricating oils being obtained in this manner. The conversion is effected in such a manner that the hydrocarbons both of the saturated and unsaturated paraffine 35 series as well as of the aromatic series are formed in continuous homologous series up to the highest boiling substances capable of economical and industrial application.

The process may also be carried out with 40 the richest carboniferous material of this kind, that is to say with coal or carbon itself, in an easy and industrially economical manner.

It is an essential condition for the successful carrying out of the process on an industrial scale that the raw material is finely distributed and in this condition is brought 45 into intimate contact with a catalyst, preferably such catalysts as will be liquid at 50 the temperature of reaction, and in particular a liquid metal. This metal, however, should not be such, as to easily form carbides, and in view thereof the use of lead will be entirely excluded as well as the use 55 of zinc, only tin, antimony and bismuth and alloys of the same being known to come up

to the requirement of being incapable of the formation of metal carbides, and of becoming liquid at the temperature of reaction. This element of my invention is of great 60 importance, inasmuch as it does entirely away with the trouble of copious carbonization which heretofore was almost unavoidable in similar catalytic processes. For the execution of the process pieces of apparatus 65 of very simple construction may be used. Thus, for example, small stills may be employed which are charged with the contact material in liquid or solid condition according 70 to the nature and composition of said contact material, but at all events in such a manner as to present an extended contacting surface to the mixture of raw material and protecting gas or fluid. In these kinds of apparatus which should be more or less 75 highly heated in accordance with the nature of the substance and the decomposition desired the substance to be decomposed is injected by blowing and by the aid of a protecting gas, such as hydrogen. The injection 80 should be effected in such a manner that an exceedingly fine spray or a fog of the substance to be treated is produced. The spraying and disintegration may be produced in different ways, such for instance, 85 by means of spraying nozzles, by pressure pumps, constructed for example in the manner of the fuel pumps employed for the Diesel engine, and by all equivalent or similar methods which produce a reliable disin- 90 tegration.

The products of reaction may be collected 95 separately and may be united according to requirements, and may, if desired, be submitted to a fresh treatment until the desired final products are obtained.

The efficiency and output of the apparatus 100 may be considerably increased by arranging a plurality of reaction vessels in parallel connection, and then effecting the union of the more or less decomposed substances only 105 in the additional reaction chambers, the vaporous or gaseous products finally obtained being then submitted to a normal condensing process with or without the usual preliminary separating apparatus. By the term "protective gas" I mean every 110 gas mixture which is adapted to avoid dehydrogenation. In accordance with my previous observations it is preferable to use a protective gas containing hydrogen. I may also make use as a protective gas of

the hydrocarbon vapors produced in the course of reaction.

It has also been found that by the new process hereinbefore outlined I am not only enabled to produce the decomposition and conversion of tar products, oil products and the like which have been sprayed and disintegrated and converted into a fog by protective gases or hydrogen, but that the gaseous and fog-like tar products discharged from gas chambers, producers, and the like may be directly submitted to the treatment. In such cases the gases generated in the gasifiers, producers, carburettors or the like in which coal, carbon, wood and equivalent substances are decomposed into gas, tar and ashes contain hydrogen with other indifferent or inert protective gases, and it is therefore not necessary to add hydrogen, but it is sufficient to introduce the mixture, as soon as it is formed, into the reaction chambers. The gas produced furnishes the hydrogen for the chemical process, and the remaining gas serves as a protecting or diluting agent. The mixture of fogs of gas and tar in exceedingly fine dispersion is then introduced into the reaction chambers by a pump or fan, located in front or between the reaction chambers or behind the same, or in any other suitable manner and is caused to pass through the reaction material and through the reaction chambers. The separation of the oily and benzine-like constituents distributed in the gas is then effected in the well known manner by cooling, washing, compression and the like. The remaining permanent gases separated off from the condensing constituents are conducted away for any usual or other utilization. It is necessary, of course, to exclude as much as possible the presence of oxygen.

Examples of execution of the process.

1. Producer tar from lignite, mixed coals, or other coal is heated until it is well liquefied and is introduced into the apparatus by means of nozzles or pressure pumps together with the mechanical impurities and in the presence of protective gas, a liquid alloy being contained in the apparatus. In the few moments of the engagement of the fog-like mixture with the contact material at a high temperature the first part of the reaction takes place. The mixture is then submitted to a further similar treatment in additional similar pieces of apparatus arranged in series with the reaction chambers first mentioned, and the number of which is governed by the degree of decomposition to which it is desired to submit the material. Olefinic, paraffine-like and aromatic hydrocarbons are thereby produced and gas which may be separated from the hydrocarbon therein by well known methods. The bodies containing oxygen and soluble in sodium hydrate

are either converted into more stable phenols and cresols or they are decomposed into hydrocarbons or lower boiling oxygen containing fractions, such as acetone and the like. The nitrogen containing bodies are either converted into hydrocarbons and ammonia or they are converted into basic bodies of different nature, but adapted for industrial utilization in the arts. Inasmuch as the procedure is continuous, it will be unnecessary to mention percentages of the output obtained, but it should be pointed out that, for instance, lower boiling hydrocarbons are formed to the amount of from 30 to 40 per cent, and that of the portions soluble in alkali lye about one half thereof on an average are converted into hydrocarbons and phenols of high value and cresol at the first stage of the procedure. Pitch and pitch-like portions and cokes are not formed, but a certain amount of hydrogenated hydrocarbons are formed which upon repeating the procedure may be converted into low boiling hydrocarbons of the kind first mentioned.

2. Crude oils containing 45 to 50% of asphaltum residues with sulphur are sprayed in the same manner or disintegrated by blowing and are introduced into the correspondingly heated reaction masses, and in the case of petroleum at temperatures, for instance of about 500 degrees centigrade. According to the amount of the substance to be treated the reaction chambers are arranged in parallel connection in the first stage, and in series connection with the following reaction chambers and stages, the several pieces of apparatus being then united in the last stage of condensing vessels. Similar to the procedure in the distillation of crude oils the different fractions are obtained, and in such a manner that no pitch-like or asphaltic masses are produced, the easily boiling fractions amounting upwards to about 50 per cent of the raw material according to the operating procedure; or the residual products belong to the series of light oils and lubricating oils, and may be further split in accordance with industrial and economic requirements, and may be decomposed into the standard trade products. In case paraffines, lignite tars or the like should be present in some of these substances, this paraffine may be separated or may be decomposed into low boiling hydrocarbons; but at any rate the separated fractions obtained, when the paraffine is separated, are of particularly high value, because the paraffines are obtained in very large crystals, and in this manner may be easily separated off even from the oils which are present in the coal tar and mineral oil products and the like.

On the accompanying drawing I have shown diagrammatically and by way of

exemplification only, and without limiting the invention thereto, a combination of pieces of apparatus for carrying out the invention in plan view. In the drawing 1 indicates a pump, blower or the like connected to the source of material to be treated. 2, 3, 4 and respectively 2', 3', 4' are indicative of two parallelly disposed sets of treating chambers, towers, scrubbers or the like containing the catalyst and suitably connected to the pump or the like 1 and also connected to each other. At the end of these two or more series of treating units the mixture of materials or the reaction products 15 may be delivered by means of a fan or the like 5 into a number of treating units 6, 7 in series connection and which are succeeded by condensers, washers or the like 8, 9. The chimney is indicated at 10. It is obvious that I am not restricted to any particular number of units, and may employ more or less of them according to varying requirements, and their relative position and the position of the pressure and suction 25 producing means is entirely immaterial for the purposes of my invention. The pressure and temperature employed are governed by the nature of the starting material and of the final products it is desired to obtain.

20 Various other changes and modifications are possible within the meaning of the claims hereunto appended and without deviating from the spirit of my invention.

I claim:

35 1. The process of treating tars, crude mineral oils and similar substances and of preventing the separation of carbon and pitchy matter in the catalytic decomposition thereof, which consists in treating these substances 40 at a high temperature and in finely distributed condition, and in the presence of a protective gaseous agent exclusively with a metal catalyzer in a substantially pure, metallic condition and incapable of forming carbides.

45 2. The process of treating tars, crude mineral oils and similar substances and of preventing the separation of carbon and pitchy matter in the catalytic decomposition thereof, which consists in treating such material at a high temperature and in finely divided condition exclusively with a metal catalyzer in a substantially pure, metallic condition and incapable of forming carbides, and in the presence of a hydrogen-containing gaseous atmosphere.

50 3. The process of treating tars, crude mineral oils and similar substances and of preventing the separation of carbon and pitchy matter in the catalytic decomposition thereof, which consists in highly dispersing such material into fog-like condition, and treating it exclusively with a metal catalyzer in a substantially pure, metallic condition and liquefying at the temperature of reaction and in-

capable of the formation of carbides, and in a hydrogen-containing atmosphere.

4. The process of treating tars, crude mineral oils and similar substances and of preventing the separation of carbon and pitchy matter in the catalytic decomposition thereof, which consists in highly dispersing such material, mixing the same with hydrogen, and treating the mixture in successive stages exclusively with a metal catalyzer in a substantially pure, metallic condition and incapable of forming carbides, and liquefying at the reaction temperature.

5. The process of treating tars, crude mineral oils and similar substances and of preventing the separation of carbon and pitchy matter in the catalytic decomposition thereof, which consists in highly dispersing such material into a fog, gas-like condition, mixing the same with hydrogen, and treating the mixture exclusively with a metal catalyzer in a substantially pure, metallic condition and incapable of forming carbides, and liquefying at the reaction temperature in separate, simultaneous stages, then uniting the resulting reaction products and then repeating the treatment in consecutive stages.

6. The process of treating tars, crude mineral oils and similar substances and of preventing the separation of carbon and pitchy matter in the catalytic decomposition thereof, which consists in highly dispersing such material in the presence of a protective gas, preventing oxidation and carbonization, and converting said material into a gas-like foggy condition, and treating the product obtained exclusively with a metal catalyzer in a substantially pure, metallic condition and liquefying at the reaction temperature, and incapable of the formation of carbides, and condensing and separating the reaction products.

7. The process of treating tars, crude mineral oils and similar substances and of preventing the separation of carbon and pitchy matter in the catalytic decomposition thereof, which consists in highly dispersing such material in the presence of hydrogen, and thereby converting said material into a foggy, gas-like condition, and treating the mixture obtained at a high temperature exclusively with a metal catalyzer in a substantially pure, metallic condition and liquefying at the temperature of reaction, and incapable of the formation of carbides.

8. The process of treating tars, crude mineral oils and similar substances and of preventing the separation of carbon and pitchy matter in the catalytic decomposition thereof, which consists in treating the mixture of highly dispersed nebulized, tar-carrying by-products from producers, gas chambers, carburetors and the like in the presence of hydrogen in finely dispersed condition exclusively with a metal catalyzer in a sub-

stantially pure, metallic condition and liquid at the reaction temperature and incapable of forming carbides, and separating solidifiable and condensable constituents from the products of reaction.

9. The process of treating tars, crude mineral oils and similar substances and of preventing the separation of carbon and pitchy matter in the catalytic decomposition thereof, which consists in treating the mixture of

highly dispersed nebulized, tar-carrying by-products from producers, gas chambers, carburetors and the like in finely dispersed condition and in a heated state with hydrogen, and exclusively with a metal catalyster 15 in the substantially pure, metallic condition and liquid at the reaction temperature, and incapable of the formation of carbides.

MICHAEL MELAMID.
